JOSEPH BERGER, JR., OF UTICA, NEW YORK, ASSIGNOR, BY MESNE ASSIGNMENTS, TO UNION SPECIAL MACHINE COMPANY, A CORPORATION OF ILLINOIS.

FEEDING MECHANISM FOR SEWING-MACHINES.

1,124,198.

Specification of Letters Patent.

Patented Jan. 5, 1915.

Original application filed August 4, 1902, Serial No. 118,236. Divided and this application filed March 19, 1903. Serial No. 148,511.

To all whom it may concern:

Be it known that I, JOSEPH BERGER, Jr., a citizen of the United States, residing in Utica, county of Oneida, and State of New York, have invented a new and useful Improvement in Feeding Mechanism for Sewing-Machines, of which the following is a description.

This invention relates to feeding mechanism for sewing machines, and more particularly to that class of feeding mechanism which is employed for operating upon different kinds or texture of goods at the same time; that is to say, goods whose mesh or texture is quite open and goods whose mesh or texture is close.

An object of this invention is to provide a feeding mechanism which is capable of feeding two pieces of different kinds of goods, or the same kind of goods, at the same time at different relative speeds.

Another object of this invention is to provide a feeding mechanism capable of either gathering or stretching either of two pieces of goods relatively.

Other objects of this invention will appear during the course of this description.

The invention consists in the elements, features and combinations hereinafter described and claimed.

In the drawings: Figure 1 is a top plan of my feeding mechanism, those parts only being shown which are related to my invention; Fig. 2 is a vertical section of Fig. 1 on the line 2—2; Fig. 3 is a similar view on the line 3—3 of Fig. 1; Fig. 4 is a plan of a section of the throat-plate showing the form and arrangement of the feed-dogs; Fig. 5 is a similar view showing another form and arrangement of the feed-dogs; Fig. 6 is a view similar to Fig. 3, showing a slight modification of the invention.

Only so much of the machine or parts are shown as are deemed necessary to illustrate my invention.

One form of my invention is shown in Figs. 1, 2 and 3, in which 1, is the rocking-frame, pivoted to the bed-plate 2, of the machine, such frame deriving its movements through any suitable connection 3, with the driving shaft 4, including the usual means

5, for regulating its rocking movement. The feed-bar 6, horizontally disposed, is pivoted, or journaled at its rear end to the upper end of the rocking frame 1, at 7; and at its forward end said bar has suitably secured thereto a feed dog 8 provided with teeth 9, as usual. On its under side, the feed-bar is provided with an angular piece 10, between which and the body of the bar an actuating eccentric, or cam 11, on the driving shaft is embraced for imparting vertical movements. Between its ends, the rocking-frame has secured thereto, in any suitable manner, a bracket-piece 12, carrying a vertically disposed bar 13, provided with a number of perforations 14, for the reception of a screw 15, carried by one end of an adjustable link 16, having its opposite end adjustably secured in like manner in any one of a series 15 of perforations 17, in a similar bar 18, suitably secured to a feed-bar 19, supported and guided in bearings 20, carried by the feed-bar 6. The feed-bar 19, is free to slide longitudinally on the bar 6 and independently thereof, but is confined by its guides so as to partake of the vertical movements of said feed bar 6; the bar 19, at its forward end, carries a feed dog 21 having teeth 22. The link 16, forms the driving connection 80 between the rocking-frame 1, and the bar 19, and as said link is adjustable on the bars 13, and 18, the amount of movement transmitted from the rocking frame to the feed-bar 19 can be regulated and varied according to 85 the character of work to be performed or the results desired. Obviously, longitudinal slots instead of apertures may be provided in the bars 13, and 18, for the adjustments; and it will be clear that the dog 21 can be 90 caused to feed fast or slow according to the position of the link 16, along the bars 13, and 18, and that its movement may be in excess of the movement of the feed-bar 6, by placing the link 16, above the pivotal 95 connection of the rocking-frame with the bar 6 as shown in Fig. 3, or may be the same as, or as much less than, the movement of said bar 6, as desired, by adjusting said link 16, along said bars 13 and 18, see Fig. 2.

It will be clear from the above description that the speed of the feed-dogs may be

changed relatively, and that the forward dog may be caused to move faster or slower than the rear-dog, this depending upon the character of the work to be performed, or 5 the results desired, or the necessities of the conditions caused by the character of the work operated upon. Moreover, it will be clear from Fig. 2 of the drawing that when the bar 18 is secured to the feed bar so as 10 to extend at right angles thereto, the feed dog 21 will be maintained in the same position relative to the needle for various adjustments of the link 16, for the reason that the bar 13 is substantially vertical when 15 the feed bar is nearest the needle. This is not always desirable and is undesirable in certain conditions and in operating upon certain kinds of work, such as in feeding edgings of open-work character, or in bar 20 stitching, when it becomes necessary to have the feed-dog operate as closely to the needle as possible. To provide for this, the bar 18, may be secured to the feed-bar 19, at an inclination, or obtuse-angle, in which case as 25 the link is lowered along the bars 13 and 18, the dog 21, will be moved toward the needle, as clearly shown in Fig. 3, thus enabling said dog to work close to the needle and engage the edging and advance the same with 30 certainty.

The feed-dogs may be of any desired shape and size and may have any desired relation to each other, such shape and relation depending entirely upon the character 35 of work operated upon or the results or effects desired. In Fig. 4, the rear-dog 9, is shown broad and extending to the outer edge of the forward dog 21, the latter being narrow and lying in front of the rear dog 40 9. In Fig. 5, the dog 34, is shown narrow and long, and the rear-dog 35, much shorter than the other dog and lying in a plane parallel with the latter but in front thereof. The particular shapes and arrangements 45 herein shown are merely illustrative of modes of carrying out the spirit of my invention and are not intended, in any sense, as limitations; for it will be clear that many changes in shape and arrangement of parts 50 can be made without departing from the principles of my invention.

From the above description and the illustration afforded by the drawings, it will be clear that adjustments may be made to cause 55 the forward dog to feed either faster or slower than the rear dog; or the latter may be given a speed of travel the same as the forward-dog or faster or slower than the latter. The relative speed of the dogs de- 60 pends upon the character of work operated upon; and this is true also of the size and shape of the dogs and the relative disposition thereof. For example, in binding a garment, or sewing edging to fabric, around

curved edges, it is important to feed the 65 binding or edging faster than the garment or fabric so as to produce neat, smooth work and avoid puckering the one relatively to the other.

Another use of my invention is in pucker- 70 ing or gathering one piece of work on or relatively to another, this being accomplished by feeding the piece to be gathered faster than the other; or one piece of work may be stretched on or relatively to the other 75 by causing one dog to move slower than the other.

From the above description it will be clear that I have produced a feeding mechanism which is simple in its elements, capable of 80 attaining high speed, and also capable of a variety of uses, and many adjustments for various effects; which effects, moreover, can be still further varied when a specialized presser-foot mechanism is employed in connection with the feed, such as shown in my application filed August 4th, 1902, Serial No. 118,236, of which this case is a division.

For the sake of clearness in terminology, and for convenience, I denominate the feed 90 dog which engages the fabric ahead of the needle, as the auxiliary feed dog, and the other feed dog which feeds away the goods after the stitching, as the main feed dog. The feed bars supporting the respective dogs 95 are also named as auxiliary and main feed bars.

Having thus described my invention what I claim and desire to secure by Letters Patent is:

1. In a feeding mechanism, the combination of a main and an auxiliary feed-bar; means for actuating said feed-bars for imparting the feed movements thereto including a rocking-frame directly connected to 105 one of said feed-bars, and mechanism connecting said rocking-frame and the other feed-bar; said mechanism including a bodily adjustable member for regulating the action of the feeding mechanism whereby either 110 feed-bar may be caused to travel faster than the other.

2. In a feeding mechanism, the combination of a main and an auxiliary feed bar, means for actuating said feed bars for imparting the feed movements thereto, including a rocking frame directly connected to the auxiliary feed bar, and mechanism connecting said rocking frame and the main feed bar, said mechanism including a bodily 120 adjustable link for regulating the action of the feeding mechanism whereby either feed bar may be caused to travel faster than the other.

3. In a feeding mechanism, the combination of a main and auxiliary feed bar, means for simultaneously raising and lowering said feed bars, means for imparting feeding

movements to said feed bars, including a rocking frame directly connected to one of said feed bars, a substantially vertical bar directly and rigidly connected to the other feed bar, a second substantially vertical bar directly and rigidly connected to said rocking frame, and a link adjustably connected to said vertical bars.

In testimony whereof I have hereunto signed my name in the presence of two sub- 10 scribing witnesses.

JOSEPH BERGER, JR.
